GEORGE HILGER, OF CHICAGO, ILLINOIS.

FLUID COMPRESSOR.

Application filed November 28, 1927. Serial No. 236,076.

The present invention relates to improvements in compressors for fluids, such as ammonia, and has particular reference to a novel compressor adapted to handle a plurality of 5 fluids having different back pressures.

In refrigerating systems, spent ammonia from different cooling devices may be returned to the compressor at different pressures. The primary object of the present invention resides in the provision of a novel 10 twin cylinder compressor which will handle fluids from different sources with as many as four different respective back pressures.

A further object resides in the provision in 15 a twin cylinder compressor of novel means for separating opposed cylinder ports and connecting said ports to independent inlet trunks or pipes.

Further objects and advantages will be 20 come apparent as the description proceeds.

In the accompanying drawings, Figure 1 is a side elevational view of a compressor embodying the features of my invention.

Fig. 2 is a plane view. 25 Fig. 3 is a detailed view in elevation on one of the partition sleeves between the opposed cylinder ports.

Fig. 4 is a fragmentary sectional view taken along line 4—4 of Fig. 6.

30 Fig. 5 is a fragmentary vertical sectional view taken along line 5—5 of Fig. 2.

Fig. 6 is a horizontal sectional view taken along line 6—6 of Fig. 5.

Fig. 7 is a horizontal sectional view taken 35 along line 7—7 of Fig. 5.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended 45 claims.

Referring more specifically to the drawings, the exemplary embodiment of the invention consists of a compressor 10 which is 50 adapted to receive fluid from four different sources normally under different back pressures. To this end, the compressor 10 is connected to four separate inlet pipes 11—12—13—14 leading to different sources (not

shown), such as cooling devices employing 55 ammonia as the refrigerant.

The compressor 10 comprises twin cylinders 15—16 in which suitable pistons 17—18 respectively are slidably disposed. In the present instance, the outer or upper ends of 60 the cylinders 15—16 are suitably closed by means of a removable head 19, and the inner ends thereof open to a crank case 20. Suitably journaled in bearings 21 in the ends of the case 20 and projecting from the latter is 65 a crank shaft 22 which is adapted to be driven by any suitable means, such as the pulley 23, and the throws of which are spaced angularly 180°. The throws of the shaft 22 are operatively connected to the inner ends of the pistons 17—18 by means of connecting rods 70 24—25.

The cylinders 15—16 are each provided with two longitudinally spaced inlet means designated respectively at 26—27 and 28—29. 75 Preferably, each inlet means comprises a set of closely spaced ports formed in the wall of the cylinder. The two sets of inlet ports 26—28 are directly opposed and open respectively to the upper ends, conveniently designated as high pressure chambers 30—31, of the cylinders 15—16; and each set of ports is so located that it will be just uncovered when the associated piston is in its innermost position. The two sets of inlet ports 27—29 are 80 also directly opposed and open respectively to the cylinders 15—16 about the pistons 17—18 and communicate at all times with the interior of the pistons, conveniently designated as low pressure chambers 32—33. To 85 this end, each of the pistons 17—18 is formed in its lower end with a peripheral space communicating with the associated set of ports in all positions of reciprocation of the piston. These spaces, designated as 34—35, communicate through large openings 36—37 with the chambers 32—33. 90

Suitable valves 38—39 are provided respectively in the upper ends of the pistons 17—18 between the high and low pressure chambers. 100 In the present instance, these valves are alike, and hence only one of the valves will be described. Each valve comprises a suitable beveled valve plug 40 adapted to rest against a valve seat 41 during the compression stroke of the piston and to be raised from said seat during the suction stroke of said piston. The seat 41 is formed at the upper end of a bore 105

42 through the end of the piston. Secured in the bore 42 is a sleeve 43 having an end wall formed with a central bearing 44 and a plurality of ports 45. The plug 40 has a depending stem 46 which extends through the bearing 44, and which has an adjustable head 47 on its lower end. A coil spring 48 is disposed on the stem 46 between the bearing 44 and the head 47, and tends to close the valve lightly. 10 It will be evident that when the pressure in the low pressure chamber is higher than that in the high pressure chamber, the valve will be open, and when the opposite condition obtains the valve will be closed. As will be apparent hereinafter, the first mentioned condition obtains during most of the suction stroke and until the upper set of inlet ports is uncovered, and the last mentioned condition obtains during the compression stroke.

15 The inlet ports 26—27—28—29 are connected respectively with the pipes 11—12—13—14. These pipes receive exhaust fluid, such as ammonia, from different sources (not shown) discharging the fluid at different pressures. For illustration, let it be assumed that there is ammonia at -6° F. and a gauge pressure of 10 pounds per in.² in the pipe 12; ammonia at -50° F. and zero gauge pressure in the pipe 14, ammonia at 34° F. and a gauge pressure of 50 pounds per in.² in pipe 11, and ammonia at 18° F. and a gauge pressure of 30 pounds per in.² in pipe 13.

20 Opening through a web 49 between the cylinders 15—16 are two bores 50—51. The bore 50 communicates at opposite sides through passages 52—53 with the two upper sets of ports 26—28; and the bore 51 communicates at opposite sides through passages 54—55 with the two lower sets of ports 27—29. Rigidly disposed in the bores 50—51 respectively are two cylindrical sleeves 56—57 formed respectively with inner diagonal dividing or partition walls 58—59 separating the opposed cylinder ports. Of the sleeve 56, the opposite ends are formed with ports 60—61 respectively opening to the passages 52—53. Similarly, the opposite ends of the sleeve 57 are formed with ports 62—63 respectively opening to the passages 54—55. The discharge ends of the pipes 11—12—13—14 are secured to the web 49 and end to end with the sleeves 56—57 by any suitable means, such as the fittings 64.

25 The low pressure inlet pipes 12—14 are connected by a shunt or by-pass pipe 65 in which a suitable valve 66 is interposed. Similarly, the high pressure inlet pipes 11—13 are connected by a by-pass pipe 67 in which a suitable valve 68 is interposed. In the present instance, the valves 66—68 are alike in construction, and hence but one will be described in detail. Preferably, each of the valves 66—68 comprises a valve fitting 69 having a valve seat 70 facing the high pressure line. 30 A valve member 71 is pivotally mounted in

the fitting 69, and normally is held by the pressure differential against the seat 70. It will be evident that if the pressure in the pipe to the rear of the seat 70 should rise above that in the other pipe, the valve will open, thereby automatically equalizing the pressure in the two pipes and admitting fluid in effect from a single line to both cylinders. 65

35 The cylinders 15—16 are provided respectively with suitable fluid discharge means 72—73. In the present instance, these two means are alike, and therefore only one will be described. Each of the means 72—73 comprises a floating valve piston 74 slidably disposed in the upper end of the cylinder 75 which is slightly enlarged to form a beveled seat 75. The piston 74 normally rests against the seat 75, in which position it covers a plurality of discharge ports 76. Disposed between the head 19 and the piston 74 is a heavy coil spring 77 which tends to hold the piston in position when the pressure in the cylinder is below a predetermined maximum, but which will permit a pressure relief past the seat 75 when the pressure rises above said maximum. The piston 74 is formed with an inner chamber 78 opening through ports 79 to the cylinder and through ports 80 to the discharge ports 76. A suitable yielding member 81 overlies the ports 79, and serves to close the latter during the suction stroke, and at all times when the discharge pressure is higher than the pressure in the cylinder. The discharge ports 76 from the two cylinders 15—16 open into a single high pressure pipe line 82. In practice, a pressure of approximately 180 pounds per in.² may be maintained in the line 82. 80 90 95

40 In operation, the lines 11—12—13—14 may receive exhaust fluid, such as spent ammonia from different cooling systems, at different pressures, for example 50 pounds, 10 pounds, 30 pounds, and 0 pounds, gauge pressure per in.². The compressor will take the fluid from these lines and compress it to a desired predetermined discharge pressure, for example 180 pounds per in.². Referring to Fig. 6, the interior of the piston 17 is constantly filled with fluid from the pipe 12. As the piston 17 moves downwardly on the exhaust stroke, the valve 72 will be closed, and the valve 38 will be opened to fill the high pressure chamber 30 with fluid from the pipe 12. The pressure in the chamber 30 at this time will be 10 pounds per in.². When the piston 17 uncovers the ports 26, the valve 38 will be closed, and the high pressure chamber 30 will receive additional fluid from the pipe 11 to raise the pressure in the chamber to 50 pounds per in.². On the compression stroke of the piston, the fluid in the chamber 30 is compressed and discharged through the valve 72 to the pipe 82. A similar cycle takes place in the cylinder 16. Thus the chamber 31 is first filled with fluid at a gauge pressure of 0 120 125

pounds per square in.² from the pipe 14, and then with additional fluid at a pressure of 30 pounds per square in.² from the pipe 13. It will be evident that the compressor 10 when 5 operating in the above manner thus conveniently handles fluids with four different back pressures.

If the valve 66 is open, the pressures in the pipes 12 and 14 will equalize, and fluid of the 10 same pressure will enter through the ports 27—29. If the valve 68 is open, the pressures in the pipes 11—13 will equalize, and fluid of the same pressure will enter through the 15 ports 26—28. In each of these events, the compressor will be handling fluids with three different back pressures. If both valves 66—68 are open, the compressor will be handling fluids with two different back pressures. By providing the valves 66—68, it will be evident that if the pressure in the pipe 11 falls 20 below that in the pipe 13, as for example when the supply of fluid to the pipe 11 is cut off, fluid from the pipe 13 will enter the pipe 11 so as to fill the chamber 30 with high pressure 25 fluid. Under similar circumstances, fluid from the pipe 14 will enter the pipe 12 so as to fill the chamber 32. Hence, the compressor will still take in fluid through the four inlets, thereby resulting in efficiency. 30 In practice, the pipes 13 and 14 are usually connected to fairly constant sources of spent fluid, and the pipes 11 and 12 may be connected to fluctuating or intermittent sources. When desired, the valves 66 and 68 may be 35 opened manually without regard to the pressure differentials.

I claim as my invention:

1. A compressor having, in combination, 40 two cylinders, each cylinder having a high pressure inlet and a low pressure inlet, the high pressure inlets and also the low pressure inlets of said cylinders being in opposed relation, a plurality of inlet pipes one for each inlet, and means comprising a partition 45 wall between each pair of opposed inlets, said means connecting the latter respectively to said pipes.

2. A compressor having, in combination, a pair of cylinders, two pistons one reciprocable 50 in each of said cylinders, two opposed inlet means opening respectively to said cylinders and adapted to be uncovered by said pistons, a sleeve having ports opening respectively to said inlet means and having a partition wall 55 between said ports, and two fluid supply pipes opening respectively to opposite ends of said sleeve.

3. A compressor having, in combination, a pair of spaced cylinders, a pair of pistons one 60 reciprocable in each cylinder, low pressure inlet means automatically operable to admit fluid to said cylinders during the suction stroke, high pressure inlet means adapted to be uncovered near the end of the suction 65 stroke to admit additional fluid to said cyl-

inders, means for supplying pressure fluid separately to each inlet means for each cylinder, and means for connecting said low pressure inlet means and also said high pressure inlet means when the occasion arises. 70

4. A compressor having, in combination, two cylinders each having two separate inlet means, said inlet means for said two cylinders being arranged in opposed relation to form pairs, two partitions one between the 75 opposed inlet means of each pair, and four supply pipes, one opening to each inlet means.

5. A compressor having, in combination, a pair of spaced cylinders, a pair of pistons one reciprocable in each cylinder, low pressure 80 inlet means automatically operable to admit fluid to said cylinders during the suction strokes, high pressure inlet means adapted to be uncovered near the end of the suction strokes to admit fluid to said cylinders, and means for supplying pressure fluid separately 85 to each inlet means for each cylinder.

6. A compressor having, in combination, two cylinders each having two spaced inlet means for admitting fluid at different times, 90 said inlet means for said two cylinders being arranged in opposed relation to form pairs, two partitions one between the opposed inlet means of each pair, inlet pipes, one opening to each inlet means, a by-pass pipe connecting 95 the inlet pipes for each pair of inlet means, and a valve in each by-pass pipe.

7. A compressor having, in combination, a pair of cylinders, two pistons one reciprocable in each of said cylinders, two opposed 100 inlet means opening respectively to said cylinders, an inlet passage opening to said inlet means, a diagonal partition wall in said passage between said ports, and fluid supply pipes opening to said passage respectively at 105 opposite sides of said partition.

8. A compressor having, in combination, a pair of cylinders, two pistons one reciprocable in each of said cylinders, two opposed inlet means opening respectively to said cylinders, a sleeve having openings communicating respectively with said inlet means and having a diagonal partition wall between said openings, two separate supply pipes opening respectively to said sleeve at opposite sides 110 of said partition wall, a pipe connecting said supply pipes, and a valve interposed in said last mentioned pipe.

9. A compressor having, in combination, a pair of cylinders, two pistons one reciprocable in each of said cylinders, two opposed inlet means opening respectively to said cylinders, a sleeve having openings communicating respectively with said inlet means and having a diagonal partition wall between said 120 openings, two separate supply pipes opening respectively to said sleeve at opposite sides of said partition wall, a pipe connecting said supply pipes, and a valve interposed in said last mentioned pipe, said valve being re- 125 130

sponsive to the pressures in said supply pipes to close when the pressure in one of said pipes is in excess and to open when the pressure in said one pipe is not in excess of the pressure in the other pipe.

10. A compressor having, in combination, a pair of cylinders, two pistons one reciprocable in each of said cylinders, two inlet

means one opening to each of said cylinders, two fluid supply pipes one connected to each of said inlet means, a pipe connecting said two pipes, and a valve interposed in said last mentioned pipe.

In testimony whereof, I have hereunto affixed my signature.

GEORGE HILGER.
